UNITED STATES PATENT OFFICE.

LEOPOLD HAUSER, OF NEW YORK, N. Y., ASSIGNOR TO LEOPOLD HAUSER AND SIMON WEIL, OF NEW YORK, N. Y., COMPOSING THE FIRM OF HAUSER & WEIL.

GARMENT-HANGER.

1,005,967.

Specification of Letters Patent. Patented Oct. 17, 1911.

Application filed September 2, 1910. Serial No. 580,192.

To all whom it may concern:

Be it known that I, LEOPOLD HAUSER, a citizen of the United States, residing at No. 168 West One Hundred and Forty-first street, New York city, in the State of New York, have invented a new and useful Garment-Hanger, of which the following is a specification, reference being made to the accompanying drawings, forming a part 10 thereof.

My invention relates particularly to a hanger in which the garment supporting bar has hooks connected thereto in such manner that the hooks can be turned angularly and folded upon the garment supporting bar in order that the hanger may occupy only a small space.

The invention is also directed to certain other structural details of the garment supporting bar.

In the drawing which illustrates a specific embodiment of my invention Figure 1 shows the hanger with the parts in the position which they occupy when the hanger 25 is in use; Fig. 2 shows the device with the parts in the position they occupy when the hanger is desired to be packed; Fig. 3 is a plan view of the hanger with the parts in the position they occupy when in use; Fig. 30 4 is a view looking at the hanger from below with one of the end members in extended position and with the other of the end members in the innermost position or the position which it occupies when the 35 hanger is to be packed; Fig. 5 is an enlarged vertical view showing the hooks and the manner that they are connected to the bar and to each other; Fig. 6 is a plan view of the plate which is utilized to connect the 40 hook B to the bar; Fig. 7 is a detail plan view of an end of the central member of the garment supporting bar; Fig. 8 is a sectional view taken on the line 8—8 of Fig. 7; Fig. 9 is a plan view of one of the end 45 members; Fig. 10 is a side view of one of the end members; and Fig. 11 is a sectional view taken on line 11—11 of Fig. 9.

In said drawing A designates the garment supporting bar which comprises the 50 central housing portion *a* and the end members *b*—*b* slidable therein. The hook designated by B serves as a supporting means for the bar A. On the under side of the garment supporting bar A is a hook C 55 which serves as a depending supporting

means from which another garment or garment hanger may be supported.

The hooks B and C have hinge connections *f* and *g* to the plates *c* and *d* respectively and these plates are connected to the 60 garment supporting bar and also to each other in such manner as to form a swivel connection between the hooks and the garment supporting bar. The plate *c* is shown in plan in Fig. 6 and the plate *d* is similar 65 in construction to the plate *c*.

It will be noted that each of the plates is provided with curved slots through which pass rivets *e*—*e* which engage and secure the plates to the bar and also secure the 70 plates to each other. The rivets, however, are not upset sufficiently to cause the plates *c* and *d* to bind upon the bar and the construction above described thus constitutes the swivel connections between the hooks 75 and the bar. It will be obvious that the hooks can be moved angularly 90 degrees as shown in full and dotted lines in Fig. 5.

The garment supporting bar A comprises a central housing member *a* formed of sheet 80 metal and the edges of this member are bent inwardly so as to serve as guide-ways for the slidable end members *b*—*b*. The end members are made by stamping from a metal plate but it is obvious that they may 85 be formed in other ways.

To prevent the end members from being pulled out of the housing stops *h* are "struck" or bent from the body of the metal in the housing and they form a simple and 90 effective means of limiting the outward movement of the end members. It will be noted that the stops have portions which are adjacent to the inner edges of the slots in the end members so that the stops may serve as 95 supplemental guide members for the slidable end members.

While I have described and shown hooks for supporting the bar and also supporting other things from the bar, still it is obvious 100 that means other than hooks may be utilized for the same purpose that the hooks are utilized and the claims are to be construed as covering such means.

It is obvious that various forms and modifications may be made without departing from the spirit and scope of my invention.

I claim as my invention:

1. A garment hanger having a garment supporting bar comprising a sheet metal 110

central section, a swiveled member having at opposite sides thereof slotted portions, a lug carried by the swiveled member, a hook hinged on said lug, and pins extending between the central section and the swiveled member to hold them together.

2. A garment hanger having a garment supporting bar, slotted plates on opposite sides of the bar connected to supporting hooks or members and a common means extending through the slots for connecting the plates to the bar so that the plates can turn relative to the bar.

3. A garment hanger having a garment supporting bar, slotted plates on opposite sides of the bar having a hinge connection to supporting hooks or members and a common means extending through the slots for connecting the plates to the bar and to each other in such manner that the plates can turn relative to the bar.

4. A garment hanger having a garment supporting bar, a supporting member connected to a plate which is located on the top

side of the bar, a depending supporting means connected to a plate located on the lower side of the bar, and means extending through the bar and both plates to hold them in place upon the bar.

5. In a garment hanger a slideable end member and a housing therefor having a stop for limiting the movement of the slideable member, said stop so constructed that there are sides thereof which can serve as guides for the slideable member.

6. In a garment hanger a slotted slideable end member and a sheet metal housing therefor, said housing having a stop struck from the metal in the housing, which stop has sides adapted to engage the walls which define the inner edges of the slot and thereby serve as a guide for the slideable member.

This specification signed and witnessed this 29th day of August, A. D. 1910.

LEOPOLD HAUSER.
